UNITED STATES PATENT OFFICE.

ARTHUR HAMMOND SHIPLEY, OF LEICESTER, ENGLAND.

BRUSH-MAKING MACHINE.

Application filed September 10, 1920. Serial No. 409,473.

(GRANTED UNDER THE PROVISIONS OF THE ACT OF MARCH 3, 1921, 41 STAT. L., 1313.)

To all whom it may concern:

Be it known that I, ARTHUR HAMMOND SHIPLEY, subject of the King of Great Britain, residing at Leicester, in the county 5 of Leicester, England, have invented certain new and useful Improvement in or Relating to Brush-Making Machines, of which the following is a specification, reference being had therein to the accompanying drawing, 10 and for which I have applied for Letters Patent of Great Britain May 21, 1917, which application has matured into British Patent No. 115,889, granted August 15th, 1918.

This invention relates to brush-making 15 machines and concerns more particularly machines used for the purpose of drilling or boring stocks, heads or backs of brushes preparatory to the insertion of tufts of bristles therein. While the invention is 20 chiefly intended for use in connection with brush-drilling machines, it is not necessarily limited to this kind of machine as it may admit of application to other machines employed in brush-making, such for instance 25 as filling machines. For the purpose of the present description however, it will be hereinafter referred to in connection with a brush-drilling machine.

The invention has reference to machines 30 of the class above mentioned wherein provision is made whereby the position of the brush head, back or stock (hereinafter referred to as the stock) may be changed relatively to the normal centre or centres about 35 which it is moved to produce radiating holes as is necessary when the tufts of bristles are to have what is known as spread, such change in position being effected without removal of the stock from the holding means.

40 In some kinds of brushes, it is desirable to insert the tufts in groups or panels arranged in different positions on the stock, and in order that the tufts in each group or panel shall have the same spread or relative angle 45 of inclination, as will be hereinafter described, it is necessary to change the position of the stock relatively to the normal centre or centres from which the holes radiate so that the holes in each group may be drilled 50 to radiate from said centre or centres. For the purpose of expediting the operation of the machine where such change of position of the stock is necessary, the present invention provides means whereby the transport

or bodily movement of the stock may be 55 rapidly effected and its different positions determined.

The invention consists, in a brush-making machine of the kind herein referred to and wherein the work-holder is capable of movement on and relative to its supporting means to change the position of the stock relatively to the centre or centres about which it is rocked and oscillated, of manually or me- 65 chanically operable means adapted to rapidly move said work-holder from one position to another, and means to determine the positions of the work-holder and hold same 70 therein.

By means of the arrangement constituting the present invention, the stock, while retained in the work-holder, may be easily and instantly moved from one position to another defined position on the supporting 75 means to bring a different part thereof into range for being operated upon as will be hereinafter fully explained.

In particularly describing the invention, reference will be made to the accompanying 80 drawings wherein:

Figure 1 is a front elevation, and

Figure 2 is a side view of a concrete embodiment of the invention wherein the work holder is arranged to be moved transversely 85 on its supporting frame.

Figure 3 is a plan of a brush-drilling machine having the movable work holder of Figures 1 and 2 applied thereto.

Figure 4 is a front view of the templet or 90 pattern board of the machine.

Figures 5 to 8 are diagrammatical views representing a brush stock and are described in detail later herein.

Figures 1 and 2 are drawn to a larger 95 scale than the remaining figures and throughout the drawings like parts are designated by the same reference characters.

It is to be understood that the invention is not to be construed as being limited to the 100 embodiment illustrated in Figures 1, 2 and 3 as such embodiment is shown and will be hereinafter described merely by way of example; other constructional arrangements coming within the scope of the invention 105 will also be described.

The form of brush-drilling machine shown in Figure 3 is a convenient one for the pur-

pose of illustrating the application of the present invention to machines of this class. In the figure referred to, 1 is the bed of the machine, 2 is the drill spindle headstock, 3 the drill spindle, 4 the drill chuck and 5 the drill. The drill spindle is driven by a belt 6 from a pulley 7 on a countershaft beneath the bed 1.

The work holder (which is best shown in Figures 1 and 2) comprises conveniently a pair of clamp devices 8 each fitted with a pair of holding members 9 relatively adjustable by means of a screw 10 to clamp upon and hold the stock S. In the form shown, the holding members 9 are provided with dogs 11, but the work holder may take other forms, the present invention concerning not so much the construction of the work holder as the arrangement and actuation of the same in a manner whereby it may be rapidly moved from one position to another.

The work holder is mounted upon the rocking and oscillating frame which also carries the templet or pattern board 12 (Figure 3). This frame in the particular machine shown, comprises side rods 13 which by means of fittings 14, support transverse rods 15 (Figures 1, 2 and 3) which carry the work holder said fittings also being provided with bosses 16 in which the rods 17, to which the templet 12 is attached, are rigidly secured. By means of further fittings 18 (Figure 3), through which the side rods 13 are adjustable, the fore part of the frame 35 constituted by the parts 12, 13, 14, 15, 16 and 17 already referred to and which form a rigid structure, can rock i. e. be moved up and down, upon a horizontal axis 19 formed by pins 20 on the opposite ends of a cross bar 21, the fittings being adapted to turn on the pins 20. The cross bar 21 is attached to two rods 22 which are adjustable through bearings 23 on a bearing plate 24 mounted by means of a pivot pin 25 on a carriage or trolley 26 arranged to run upon wheels along a suitable track 27 on a track plate 28 fastened upon the bed 1. The pivot pin 25 forms the vertical axis upon which the work carrying frame as a whole can turn as indicated by the dotted lines it being understood that for obtaining the vertical spread of the holes the fore part of the frame is rocked on the horizontal axis 19, while for obtaining the horizontal spread of the holes in the stock, the whole frame is oscillated upon the vertical axis 25.

For convenience the rocking and oscillating work carrying frame is shown mounted upon the movable carriage or trolley 26 which forms the subject of my co-pending application Serial No. 409,474, but it is obvious that it may be otherwise mounted as this feature does not form part of the present invention.

In drilling the stock S the latter is drawn

on to the drill 5 by pulling forward the work carrying frame which longitudinal movement is permitted by the travel of the carriage 26, the position of each hole to be drilled being determined by corresponding holes in the templet 12 said holes being used in conjunction with a fixed pointer pin 29 mounted in a standard 30 upon the bed 1. After each hole is drilled the work carrying frame is moved on either or both the axes 19, 25 to bring other holes into line with the pin 29.

As illustrating the purpose for which the present invention is to be employed, a convenient example of a brush stock having a paneled arrangement of holes is shown diagrammatically in Figures 5 to 8. Figure 5 is a face view of the stock S and the circles represent the positions of the holes. Figure 6 is a vertical side view of the same stock the radiating centre lines indicating the spread of the vertical row of holes on line a—a of Figure 5. Figure 7 is a longitudinal section on line b—b of Figure 5, the centre lines here indicating the spread or radiations of the horizontal row of holes. Figure 8, to which reference will be made shortly, is a longitudinal section on line c—c of Figure 5.

In the arrangement of holes represented in Figure 5 the marginal rows 31 and 32 are drilled to radiate from a line which passes through the centre 33 of the stock, this being clearly shown in Figures 6 and 7 which indicate the vertical spread and horizontal spread respectively. In drilling these marginal holes the templet or pattern board represented in Figure 4 is used, the stock S is positioned centrally in the work carrying frame as shown by full lines in Figure 3 and the outer series of holes 34 and 35 in the templet are brought in succession on to the pin 29.

Referring again to Figure 5 the holes composing the two separate groups or panels situated within the lines d and e while having the same vertical spread as the holes in the vertical rows 32 are required to have a different spread from the horizontal rows of holes 31, for instance it may be desired that the holes in each group d, e shall radiate from a line passing through the centres 36, 37 of the respective groups as represented in Figure 8 where the centre lines indicate the angles of spread or radiations of the holes along the line c—c of Figure 5. It will be noticed by referring to Figure 8 that although the radiations of the holes in one of the groups or panels is identical with those of the holes in the other group, the radiations of the holes in both groups are distinct from those of the holes in the marginal rows 31 set out in Figure 7.

To produce the separately grouped radiations referred to the same templet 12 is employed this being provided with a centrally

disposed group of holes 38. This single group of holes enclosed within the line f is used to determine the positions of the holes in both the groups d and e but in order to obtain the desired horizontal spread of the holes in each of said latter groups, the stock S is altered in position in the frame by being transported bodily whereby the centre of each panel is brought into line with the normal centre of the frame which is of course the line from which holes positioned on either side of it will radiate. Thus by transporting the stock first one series and then the other series of holes composing the groups d and e may be formed by means of the holes in the group 38 in the templet.

For the transportation of the stock S in the manner described, the work holder is movable bodily in the frame to which end, in the embodiment shown in Figures 1, 2 and 3, the two clamp devices 8 are connected by bars 39, 40 (Figures 1 and 2) and are freely slideable to and fro along the rods 15 before referred to. The movement of the work holder i. e. the complete structure formed by the clamp devices 8 and the bars 39, 40, along the rods 15, is effected by means of a hand lever 41 pivotally attached at 42 (Figure 1) to the bar 40 its lower end having pivotal connection with one end of a link 43. The opposite end of the link is fulcrumed at 44 on a rigid support 45 and it will be seen that by simply turning the hand lever 41 in one direction or the other from the perpendicular position the work holder will be at once shifted in the same direction along the rods 15. In Figures 1 and 3 the work holder is shown in the normal central position by full lines such position being suitable for forming the marginal holes 31, 32 (Figure 5) in stock S . In the same figures the work holder is shown by dotted lines in the position it would be transported to for holding the stock while the holes in group d were being formed, the dotted lines in Figure 3 indicating also the position of the work carrying frame and the stock in relation to the drill forming the innermost holes 46 of the group d .

For holding the work holder in its respective positions a spring controlled detent or catch 47 (Figures 1 and 2) on the hand lever 41 co-operates with an arcuate plate 48 situated behind the lever and secured to the work holder by the screws 49 which attach the bar 39 to the clamp devices 8. The detent or catch 47 engages with notches 50 in the edge of the plate 48 to determine the proper position of the work holder and maintain it therein. The catch is disengaged from the notches by being turned on its pivot 51 (Figure 2).

In order that the distance between the connected clamp devices 8 may be varied to suit brush stocks of different length, the con-

necting bars 39, 40 and the plate 48 are each provided near their ends with a series of holes 52 through any one of which the screws 49 may be passed to attach the clamp devices to the bars.

The invention is not, of course, limited to the formation of a stock having an arrangement of holes such as described with reference to Figures 5 to 8, as it will be apparent that by means of a movable work holder and means for actuating the same such as shown in Figures 1 and 2, the stock may be readily and accurately transported bodily, without removal from the work holder, to bring any part throughout the length of the stock into position on the centre line for the formation of holes in said part which radiate from the centre line thereof, the arcuate plate 48 having notches suitably disposed in its edge to define the positions of the work holder on the frame.

What I claim then is:—

1. In a brush-making machine, in combination, supporting means capable of oscillation about a supporting centre or centres, a work-holder capable of movement on said supporting means to change the position of the work relatively to the centre or centres about which said means are oscillated transversely to a radius but in the plane of oscillation and means adapted to rapidly move said work-holder from one position to another.

2. In a brush-making machine, in combination, supporting means capable of oscillation about a supporting centre or centres, a work-holder capable of movement on said supporting means to change the position of the work relatively to the centre or centres about which said means are oscillated transversely to a radius, but in the plane of oscillation, means adapted to rapidly move said work-holder from one position to another on the supporting means, and means to determine the positions of the work-holder and hold same therein.

3. In a brush-making machine, in combination, supporting means capable of oscillation about a supporting centre or centres, a work-holder capable of movement on said supporting means to change the position of the work relatively to the centre or centres about which said means are oscillated transversely to a radius, but in the plane of oscillation, manually operable means adapted to rapidly move said work-holder from one position to another on the supporting means and means to determine the positions of the work-holder and hold same therein.

4. In a brush-making machine, in combination, supporting means capable of oscillation about a centre or centres, a work-holder capable of movement on said supporting means to change the position of the work relatively to the centre or centres

about which said means are oscillated transversely to a radius, but in the plane of oscillation, mechanically operable means adapted to rapidly move said work-holder from 5 one position to another on the supporting means, and means to determine the positions of the work-holder and hold same therein.

5. In a brush-making machine, in combination, supporting means capable of oscillation about a centre or centres, a work-holder slideable on the supporting means to change the position of the work relatively to the centre or centres about which said 10 means are oscillated transversely to a radius, but in the plane of oscillation, a pivotal hand-lever to move said work support, and a notched plate with which said hand-lever co-operates to define the positions of said holder and fasten it therein.

6. In a brush-making machine, in combination, supporting means capable of oscillation about a centre or centres, a work-holder slideable on the supporting means to 15 change the position of the work relatively to the centre or centres about which said means are oscillated transversely to a radius, but in the plane of oscillation, a pivotal hand-lever on the work-holder, a 20 link connecting said hand-lever with the supporting means, a notched plate on the work-holder, and a spring operated catch

on the lever adapted to engage the notches in said plate, substantially as and for the purpose described.

7. In a brush-making machine, in combination, supporting means capable of oscillation about a centre or centres, a work-holder slideable on the supporting means to change the position of the work relatively 25 to the centre or centres about which said means are oscillated transversely to a radius, but in the plane of oscillation, a manually operable member situated near the templet or patternboard of the machine, and 30 mechanism intermediate of said member and the work-holder for actuating the latter.

8. In a brush-making machine, in combination, supporting means capable of oscillation about a centre or centres, a work-holder slideable on the supporting means to change the position of the work relatively 35 to the centre or centres about which said means are oscillated transversely to a radius, but in the plane of oscillation, and 40 mechanical means which operate in a semi-automatic manner for actuating the work support, substantially as described.

In testimony whereof I affix my signature in presence of two witnesses.

ARTHUR HAMMOND SHIPLEY.
